UNITED STATES PATENT OFFICE.

FRANK S. CLARKSON, OF BALTIMORE, MARYLAND, ASSIGNOR OF ONE-HALF
TO FRANK B. SLOAN, OF SAME PLACE.

MORTISING-MACHINE.

SPECIFICATION forming part of Letters Patent No. 249,306, dated November 8, 1881.

Application filed August 22, 1881. (No model.)

To all whom it may concern:

Be it known that I, FRANK S. CLARKSON, of Baltimore city, State of Maryland, have invented certain new and useful Improvements in Mortising-Machines; and I hereby declare the same to be fully, clearly, and exactly described as follows, reference being had to the accompanying drawings, in which—

Figure 1 is a front elevation of the machine. Fig. 2 is a side elevation of the same. Fig. 3 is a plan of the work-table. Fig. 4 is a plan and elevation, showing the form of the mortise the machine is designed to cut; and Fig. 5 is a similar view of the gage.

My present invention relates to mortising-machines in general, and in particular to that class of the same in which the wood is cut by means of a revolving and laterally-cutting bit; and it has for its object to produce a machine adapted to perform a class of work heretofore only accomplished by the slow, laborious, and costly method of hand-chiseling. I refer to making the mortises for the reception of ordinary door or drawer locks.

The machine about to be described is especially designed for cutting the mortise to receive the lock patented to me and Frank B. Sloan, assignee of half interest, July 26, 1881, No. 244,855. The said lock differs from the ordinary furniture-lock in certain particulars, which adapt it for insertion in a machine-made mortise, such as that formed by the machine about to be described. In locks of this class the top plate of the lock is countersunk in the edge of the door or drawer, and the casing which contains the lock mechanism occupies a mortise on the inside, the face-plate resting upon the surface of the wood and not being sunk flush with the same. A mortise made by a laterally-cutting bit is necessarily rounded at the ends, so the lock adapted for insertion in such a mortise is rounded at the sides or has its top plate provided with rounded tangs, as shown in the said Letters Patent. Furthermore, the top plate is wider than the thickness of the casing which contains the lock mechanism. To cut the mortise for such a lock I provide two revolving bits, a suitable carrier for the work, and stops for limiting the motions of the carrier. The motions of the carrier with ref-

erence to one of the bits are three—namely, one parallel to its axis and the other two at right angles to each other and to the first. The motions with reference to the other bit are two—parallel to the axis of the bit and at right angles to it—and the two bits are at right angles to each other. I am thereby enabled at one operation to cut a mortise of the exact shape and size of those portions of the lock which are countersunk in the wood, and to form a key-hole accurately opposite the key-pin of the lock. The importance of this result may be inferred from the fact that the cost of inserting a cheap lock by hand—say the Eagle, 72—exceeds that of the lock itself. A further saving in time results from the use of my machine, as it obviates the necessity for measuring and marking the place for the lock. I simply set the gages or stops, which being properly done, the mortise has necessarily the proper location, size, and shape.

In the drawings, A is a suitable support, in which are mounted two shafts, a D, at right angles. The shaft a carries a pulley, B, for the driving-belt, and a second pulley, B', over which is led a belt to the pulley c of the shaft D. A pair of pulleys, C, which are mounted in the upper corner of the frame, serve to turn the belt.

In the ends of the shafts a D are suitable clutches for holding the bits d d', which are adapted to bore longitudinally as well as laterally. Dovetail guides e are formed on the front of the frame A, in which slides vertically the block E, having transverse guides f on its upper side. A block F'', which supports the work-plate F, slides laterally upon these guides, and the plate F slides longitudinally upon guides f'' in the top of the block F''. F' is a lever, pivoted to the main frame and engaging with the block E. It is provided with a counterpoise to balance the block and table in the usual way.

G is a lever, having a ball-joint, g, in a lug attached to the block F'', and a second ball-joint at its fulcrum g' on the frame A, whereby the lever has a universal motion and serves to lift the work-table vertically as well as to slide it laterally. The motion of the work-table on the slides f'' is effected by means of a sec-

ond lever, H, pivoted at h and fulcrumed at h'. The balls g' on the lever G and h' on the lever H are made somewhat larger in diameter than the ends of the levers, and the sockets in which 5 the balls rest are not round, except in cross-section. This construction is necessitated by the fact that the pivotal points at g and h slide transversely past the sockets, and provision is made by the described construction for a sliding motion of the balls within the sockets as the levers are moved.

It will be readily understood that upon moving the levers G and H the work-table may be moved in any desired direction. Now, in order 15 to determine the direction and extent of these motions, I provide the gages shown in Fig. 5 in plan and elevation. A plate, l, is attached by bolts through the holes j j' to the main frame, and in its face is a recess, 1, of the ex- 20 act depth of the top plate of the lock, and a second recess, 2, of the shape and size of the casing which contains the lock mechanism. A stud, i', is secured to the table in a horizontal position, and is adapted to enter these recesses, 25 and a second stud or stop, i, is also secured to the table in a vertical direction.

In Fig. 4 is shown in plan and elevation the shape of the mortise, which will be recognized as the precise shape of the countersunk portions of the lock hereinbefore referred to. The recess 4 has rounded ends, and is situated at a slight distance from the edge of the wood. The recess 5 is countersunk from the side of the wood and holds the lock-case, and 6 is the key-hole. It is obvious, however, from the fact above stated, that the table can be moved in any direction; that upon changing the form of the gage any desired form of mortise may be made.

40 In operation the board to be mortised is laid on the table F, against suitable pins or stops or clamps n, which determine its position upon the table, and are made movable and removable, so as to suit different kinds of work. The 45 bits are then set in motion, and the table is thrust by means of the lever H toward the horizontal bit d', which enters the face of the wood. The pin or stud i' meantime enters the recess 1 in the gage l and limits the forward 50 motion of the table. As soon as the stud abuts against the base of the recess the table is moved laterally in both directions until the stud abuts against the ends of the recess. The table is then raised slightly to bring the stud opposite

the recess 2, where the table is moved forward 55 and laterally, causing the stud to traverse that recess in the same manner as the first, when the mortise is complete, so far as containing the lock is concerned. Finally, the table is lifted vertically, the stud entering the slot 3 of the 60 piece M, and the key-hole is bored by the bit d, its location being determined laterally as well as longitudinally with reference to the mortise by the studs i i'. The stud i may be made to limit the forward motion of the table 65 by abutting against the frame A, or a stop secured upon it, as will be readily understood. Inasmuch as the position of the key-pin in the various standard locks is slightly different, I provide for a shifting of the key-hole with reference to the mortise by simply forming the slot 3 in a separate gage, M, attached to a plate, L, which latter is secured to the gage l by screws l', as shown. The studs and gages are made removable, so that others may be substituted for them in cutting mortises of different shapes.

70 What I claim is—

1. In a mortising-machine, a pair of bits mounted at right angles to each other, and a 80 work-table, and mechanism for moving the same in three directions at right angles to each other, two of the said motions being parallel to the axes of the bits, whereby in cutting mortises for the insertion of locks the lock-cavity and 85 key-hole are formed at one operation, as set forth.

2. In combination with the main frame, having the two laterally-cutting bits and the slides e, the blocks E F'', having transverse slides f f', 90 and the table F, as set forth.

3. In combination with the table, movable in three directions at right angles to each other, and having stud i', the gage provided with a recess representing the lock-cavity, and a gage 95 to determine the vertical cut for the key-hole, as set forth.

4. In combination with the table, the vertically-movable block E and the intermediate sliding block, F'', the levers H and G, the latter having ball-joints g g', as and for the purpose set forth.

FRANK S. CLARKSON.
